Patented July 16, 1918.

UNITED STATES PATENT OFFICE.

ALBERT MALSIN, OF NEW YORK, N. Y.

CORSET-CLASP.

1,272,831.

Specification of Letters Patent. Patented July 16, 1918.

Application filed June 9, 1916. Serial No. 102,626.

To all whom it may concern:

Be it known that I, ALBERT MALSIN, a citizen of the United States, and resident of New York, in the county of New York 5 and State of New York, have invented certain new and useful Improvements in Corset-Clasps, of which the following is a specification, reference being had herein to the accompanying drawing.

10 My present invention has reference to a clasp or fastening device for corsets and other similar garments or other articles. The object is to furnish a clasp or fastener, all of the hooks or connections of which can 15 be simultaneously and instantaneously released by the action of the various parts so that the corset may be readily unfastened and removed. Other objects will appear in the course of the description of the construction and relative arrangement of the various parts. The invention therefore consists 20 essentially in a corset clasp or fastener having several interengaging members all of which are capable of being simultaneously released by the action of certain of the parts; and it also comprises numerous details and peculiarities in the construction, arrangement, and combination of the various parts and mechanical elements, substantially 25 as will be hereinafter described and then more particularly pointed out in the claims.

In the accompanying drawing illustrating my invention:

30 Figure 1 is a front elevation of my improved corset clasp or fastener with the various parts engaged in the position that they take when the corset is fastened together. 35 Fig. 2 is a detail front elevation of the upper part of the same device showing the members of one pair of clasping features disengaged from each other to illustrate more fully the precise construction of the various 40 parts.

Fig. 3 is a vertical section on the line 3, 3 of Fig. 1.

Fig. 4 is a horizontal section on the line 4, 4 of Fig. 1.

Fig. 5 is a partial elevational view of the upper end of the clasping device with the members of one pair of clasping features in engagement with each other, and illustrates a modification of the invention.

Fig. 6 is an edge view in partial section on the line 6, 6 of Fig. 5.

Fig. 7 is an enlarged vertical detail section of the engaging ends of the two members of one eye part.

Fig. 8 is a sectional plan similar to Fig. 6 of a modified form of the invention.

Similar characters of reference designate corresponding parts throughout the different figures of the drawing.

In referring to my invention in corset 65 clasps I have particular reference to a fastening device whose function it commonly is to connect together the meeting edges of the front of a corset. It will be readily seen that the device is applicable to other garments and articles of wearing apparel. Such a fastener ordinarily comprises a steel 70 or metallic strip on one edge of the corset having pins or catch devices for engaging eye members carried by a steel or other strip 75 on the adjoining edge of the corset, the pins or catch devices being inserted into all of the eyes of the series so that the meeting edges of the corset may be brought together neatly and effectively from top to bottom, 80 but the procedure of causing the series of pins to engage the eyes is one attended with considerable difficulty, especially if a corset is tightly laced, and the disengagement of the same is equally laborious and troublesome. I therefore provide an improved 85 mechanism for these features so that the several eyes of the series of eyes may be simultaneously opened and thus the engaging pins on the other edge of the corset 90 quickly released all at once so that the corset may be promptly opened by one single swift movement of certain mechanical members which thus open all the eyes and release the pins, the easy retraction of the 95 edges from each other when this takes place being expedited and assisted by the expansion of the sections of the corset which en-

sues as soon as the clasping features are disengaged.

In explaining the detailed construction of the parts of my improved clasp, it will be seen that a strip of steel or other metal or material 3 is attached to one edge of the corset structure, the attachment being made in any suitable manner, as for instance by sewing the steel 3 to the fabric of the corset through the use of perforations 20 in the ends of part 3 and at other points if desired. Overlying the steel 3 and slideable thereon is a similar strip of steel or other metal or material 6 which slides easily on the steel 3, being guided by the bent-over edges 4 of steel 3 which furnish ways for the strip 6, as clearly shown in Figs. 2 and 4. These guides 4 are discontinuous, appearing only at intervals in order that they may not materially affect the flexibility of the members 3 and 6. In lieu of the bent edges 4 I may substitute other guides if desired, as for example the pins 18 fixed in the strips 3 and projecting through slots 17 in the outer steel 6, said pins 25 being headed and said pins and slots being preferably staggered, as indicated in Fig. 5, so that they may be near the edges of the members and thus may hold the surfaces of the members 3 and 4 more closely together than they might do if these slots and pins were located centrally. Other forms of guides for enabling the strip 6 to slide easily back and forth upon the strip 3 may be devised and substituted if desired, and I wish 30 to cover broadly the idea of so arranging these two strips relative to each other that the outer one may slide easily upon the inner one. At the upper end of the outer strip 6 is a catch 8 pivoted to strip 6 at 9 and having a snap button 10 that passes through an opening 19 in the members 3 and 6 as indicated in Fig. 3 for the purpose of holding the two members in a relatively predetermined position and preventing the outer one 35 from sliding out of position. The end of the catch is slightly bent so that it may be easily grasped for the purpose of withdrawing the member 10 from the opening 19, after which, by using the catch 8 as a handle, the strip 6 can be slid up and down upon the strip 3. Of course it is very necessary to have the button 10 or its equivalent to hold the parts 3 and 6 together, and it is also important to have a handle 8.

55 At intervals, which may be of greater or less length, along the edges of these combined steel strips 3 and 6 adjoining the edge of the corset to which they are applied, are formed eye members that constitute part of the clasps, and each of these eye members consists of a projection 5 integral with or riveted to the steel 3 in a horizontal position and a contiguous horizontal projection 7 made integral with or riveted to the outside

face of the steel 6. Although these members 65 are secured to the steel strips 3 and 6 crosswise thereof as I have said, yet it is not always desirable that they should be so shaped that they will slide over each other in parallel planes as they are indicated in Fig. 4, 70 but oftentimes it will be preferable to bend them slightly at the points where they leave the strips 3 and 6 so that the projecting portions thereof will lie in the same plane with each other, so that when the said projections 5 and 7 move together they will not be offset from each other but will be directly opposite in the same vertical plane as indicated in Fig. 8. The opposing edges of each pair of projections 5 and 7 are recessed and 75 shaped so as to form an eye, the projection 5 having a semi-circular recess 14 which coincides with the semi-circular recess 13 in the projection 7 when the parts are brought together, see Fig. 2, and the edges beyond 80 these recesses 13 and 14 being separated so as to provide a slot 16 having parallel edges. The outer end of each projection 7 is bent to form a lug 12 which engages the bent end 11 of the adjacent projection 5 as shown in 90 Fig. 4, the edges of this lug 12 being slightly beveled at the end, see Fig. 7, so as to allow it more easily to slip into the recess in the bent end 11. The bent end 11 is curved to prevent strain on either part 11 or part 12 95 when they are so engaged. Furthermore, it will be noted that the end 11 is beveled off at 15 so that the pins on the other strip may have an easier opportunity for withdrawal without catching as I will presently explain. It will be obvious that when the sliding steel 100 6 is moved back and forth or up and down over the steel 3 the projections 7 will be moved back and forth with relation to the projections 5, and consequently the lugs 12 105 on the ends of the projection 7 will engage with and disengage from the ends of the projections 5, thus forming and unforming the eye members along the edges of the steels 3 and 6. When the pairs of members 110 5 and 7 are brought together to form the eyes the clasping device will be as shown in Fig. 1 where the corresponding part 1 of the clasp on the other edge of the corset can be brought into engagement with the eyes for 115 fastening the corset together.

This other part on the other edge of the corset consists of the usual steel strip 1 of a length similar to that of the strip 3 and attached to the fabric of the corset in any 120 desired manner as by stitching or otherwise, and this steel is furnished at intervals corresponding to the eyes and located opposite thereto with horizontal projections 2 consisting of headed pins, the heads of which 125 will readily pass through the eyes but are larger than the slots 16 communicating with said eyes so that while they can be inserted

through the eyes they will then be permitted to pass into the slots 16, and thus the clasping will be effected. When the device is in readiness to be used and the eyes 5 are in normal receptive condition, the member 1 with its headed pins 2, that is to say, the edge of the corset carrying these catch pins, can be brought close to the other edge and the pins caused to engage the eye members as I have already indicated. When so 10 inserted the natural expansion of the corset under the pressure of the wearer and due to the effect of the lacing will obviously cause the headed pins to slip into the outer ends of slots 16 and be held there firmly so that the corset will be tightly fastened together. With other corsets as now in common use 15 when the headed pins have engaged the eyes there is often a great deal of difficulty in 20 disengaging them on account of the tension of the connection which makes it necessary to unfasten them individually and is a fatiguing operation. With my improved combination, however, all that the wearer needs 25 to do is to disengage the catch 8 and cause the member 6 to slide upon the member 3, the result of which will be to separate the parts that constitute the eyes, that is to say, 30 separate the projections 7 from the projections 5 by lifting the lugs 12 on the ends of the projections 7 away from the bent ends 35 of the projections 5 which will set free all of the headed pins and allow the two edges of the corset to immediately separate and 40 permit instant removal. Sometimes at this point in the operation if the pins 2 are riding on the upper edges of the projections 5, the head of the pin being within the bent end 11 of projection 5 might come into contact with the inner wall of the recess in end 45 11 and cause an obstruction to the removal of the pin 2. It is to avoid this possibility that I obliquely cut off the upper edge of outer part of the bent end 11 at 15, as shown 50 in Figs. 1 and 2, so that while the pin is sliding along the upper edge of the projection 5, the head of said pin will slip out easily through the opening at 15 and the parts will all be readily and quickly disconnected.

I have already indicated that various guiding means for the outer steel 6 may be employed and that Fig. 5 shows a modification where staggered slots are engaged by 55 staggered pins which keep the contacting surfaces of the two parts 3 and 6 close to each other, because the staggered pins are near the edges of the parts, and said edges are not apt to lift away from each other 60 from warping or other influences as might be the case if the guide pins were located along the central line of the parts 3 and 6. It will also be noted that in case the parts 5 and 7 of the eyes should not lie

alongside of each other, as shown in Fig. 4, 65 so as to overlap but should be placed one above the other in a vertical plane as indicated in Fig. 8 the outer bent end 11 of the projection 5 will have to be shaped accordingly so that the engaging lug 12 of the projection 7 might easily drop into the end 11. This can easily be done, however, by slight 70 changes in the form and shape of the parts.

Many changes may be made in the precise construction of the various steel or other 75 members, the projections, and other parts, without exceeding the scope of my invention and I, therefore, reserve the liberty of modifying and changing the structural details 80 within wide limits so as to secure the best results in practice and make the invention as useful as possible.

Having thus described my invention, what I claim as new and desire to secure by Letters Patent, is:—

1. In a corset clasp, the combination of a strip having a series of projections, a second movable strip having also a series of projections located contiguous to the first series of projections, said projections being recessed and the members of each pair having separated edges to provide an opening and a communicating slot and means for locking the two strips together consisting of a catch pivoted to one strip and having a snap 90 button adapted to pass through coincident openings in the two strips for the purpose of holding the latter in a relatively predetermined position and preventing the outer one from sliding out of place, and a strip 95 having headed pins that engage the spaces between the projections on the aforesaid strips and are released when the latter are opened.

2. In a corset clasp, the combination of a strip having a series of projections, a relatively movable strip having also a series of projections, said projections having their opposite edges recessed so as to jointly form eyes and the outer ends of certain of the 110 projections being hooked to receive the curved ends of the adjoining projections, and a strip having pins that engage the eyes and are released when the latter are opened.

3. In a corset clasp, the combination of a strip having a series of projections, a relatively movable strip having also a series of projections forming with the other projections a plurality of eyes, the outer ends 120 of one projection of each pair having a curved end, and the outer end of the other projection of the pair having a hooked end to engage said curved end, said curved end having a beveled tip, and a strip having a series of headed pins that engage the eyes and are released when the latter are opened.

4. In a corset clasp, the combination of

4
a strip having a series of projections, a second strip sliding on the first and having also a series of projections which form with the other projections a plurality of eyes, guides on the first strip for controlling the movement of the second strip, and means for locking the two strips together consisting of a catch pivoted to one strip and hav-

ing a snap button adapted to pass through coincident openings in the two strips for the purpose of holding the latter in a relatively predetermined position and preventing the outer one from sliding out of place. 10

In testimony whereof I hereunto affix my signature.

ALBERT MALSIN.
